(57) **CLAIM**

The ornamental design for a disposable dental tray, as shown and described.

DESCRIPTION

FIG. 1 is a top plan view of a “disposable dental tray” showing my new design in its fully opened position;
FIG. 2 is a bottom plan view thereof;
FIG. 3 is a front elevational view thereof;
FIG. 4 is a right side elevational view thereof;
FIG. 5 is a left side elevational view thereof; and,
FIG. 6 is a perspective view showing the tray in its closed position.
